UNITED STATES PATENT OFFICE.

ISAAC A. GEORGE, OF GOSHEN, INDIANA.

BEARING.

1,091,830.

Specification of Letters Patent. Patented Mar. 31, 1914.

Application filed February 14, 1910. Serial No. 543,665.

To all whom it may concern:

Be it known that I, ISAAC A. GEORGE, a citizen of the United States, residing at Goshen, in the county of Elkhart and State 5 of Indiana, have invented a certain new and useful Improvement in Bearings, of which the following is a full, clear, concise, and exact description, reference being had to the accompanying drawings, forming a part of 10 this specification.

My invention relates to roller bearings and has for its objects the provision of an improved formation of the roller container and the race way structure.

15 My invention, in its preferred embodiment, includes a cup and cone, one of these elements, preferably the cone, constituting the roller container, though I do not wish to be limited in all embodiments of my invention to a structure in which the race way elements are of conical formation.

20 My invention, in its preferred embodiment, is an improvement upon the invention disclosed in my United States Patent No. 25 796,995, dated August 15, 1905.

My invention may be employed in the construction of thrust bearings, hub bearings, 30 bearings for line shafting and in the construction of bearings for other purposes which need not be mentioned.

The element of the raceway which constitutes the container is made of a piece of metal with the portions margining its edges overturned to afford annular spaces into 35 which the ends of the rollers project. The ends of the rollers within these annular spaces are desirably spaced apart by other rollers, which latter rollers are preferably in the form of balls. The roller container 40 portion of the structure is desirably formed by drawing sheet metal, first into the form of a tube, and then by successive steps into the finished form in which the portions margining the edges are overturned for the 45 purpose stated.

In the preferred embodiment of the invention, the cup, which desirably does not constitute the roller container, is of conical or tapering formation presenting an inner 50 conical or tapering bearing surface to the rollers, whose ends extend into the aforesaid annular spaces with which the container is provided, the inner conical or tapering bearing surface of the cup and the rollers

having similar inclinations so that said 55 rollers have extended bearing engagement longitudinally thereof with the inner bearing surface of the cup. The outer surface of the cup transverse to the edge portions of the cup is desirably parallel to the inner 60 surface of the cup, and the housing or support for the cup is provided with a supporting surface or seat that is inclined similarly to the outer surface of the cup and desirably projects in both directions beyond 65 the outer surface of the cup when the cup is in position, this arrangement permitting the cup automatically to center itself within its seat and with respect to the axis of the rotating element, such as a shaft or journal, 70 that finds support upon the cup seat through the intermediation of my improved bearing comprising the cup, the rollers, and the roller container. I do not wish to be limited, however, in all embodiments of my invention, 75 to a construction in which the cup is provided with a cup seat, as the roller container which I have devised may be of service irrespective of the construction of the balance of the bearing.

I will explain the above features of my invention more fully by reference to the accompanying drawings showing two different preferred embodiments of my invention, and in which other features of the invention are illustrated, Figure 1 being a longitudinal section of a structure embodying the invention; Fig. 2 being an enlarged detail of part of the structure shown in Fig. 1; Fig. 3 being a sectional view on line 3 3 80 of Fig. 2; and Fig. 4 being a view illustrating another form of the invention.

Like parts are indicated by similar characters of reference throughout the different figures.

Referring first to the form of the invention shown in Figs. 1, 2 and 3 inclusive, I have there illustrated bearings in supporting relation with one end of a shaft *a*, such as a vehicle shaft, the shaft, in the embodiment of the invention now being described, being non-rotatable, the hub portion of the wheel including flanges *b* *c* between which the spokes *d* of the wheel are inserted. The flange *b* is integrally formed with a tubular 100 housing *e*, the flange *c* having a continuation *c'* extending longitudinally of and being slipped upon the outer end of the tubular

housing *e* and being secured in position by means of bolts *e*². The inner end of the tubular housing *e* is provided with an interior thread to afford lodgment for the dust cap *f* which holds a felt packing *f'* that is in contact with the shaft *a* to prevent dust from entering the housing *e* along the shaft *a*. The other end of the housing *e* is sealed by a cap *e'*. The shaft *a*, in the embodiment of the invention being described, has a pair of conical or tapering seats *g* *h*, the conical or tapering seat *g* being integrally formed with the shaft, while the other seat *h* is separately formed and is in the shape 15 of a split sleeve, so that it may have spring engagement with the shaft. The seat surfaces of the portions *g* and *h* taper toward each other and slope similarly to the inner conical or tapering surfaces of the bearing 20 roller containers *i* *k* that retain the rollers *l* *m* respectively, these rollers of each of the sets *l* and *m* tapering toward the rollers of the other set. The portions *i* *k* margining the edges of the containers *i* and *k* are curled 25 or overturned so as to overlie the portions of these containers that intervene between these marginal portions to constitute annular spaces or pockets surrounding the shaft *a* and receiving the extended portions of the 30 rollers *l* and *m* which are spaced apart by rollers *n*, which latter rollers are preferably in the form of balls that engage reduced extensions of the rollers *l* and *m* as set forth in my aforesaid patent. The roller containers, together with the rollers they contain, thus constitute self contained units of 35 the bearings, said containers constituting raceway wall portions, the raceway structure being completed by additional raceway walls *o* that are desirably separately formed from the housing *e*, though I do not wish to be limited to this characteristic. When the raceway walls *o* are separately formed from the housing *e*, the cups are, in the present 40 form of the invention being described, in the shape of conical rings, desirably of uniform thickness so that the outer and inner surfaces thereof that are transverse to the edges thereof are parallel, these surfaces so sloping that the inner surfaces will engage 45 the rollers *l* and *m* and the outer surfaces will be received by conical or tapering seats *p* that taper similarly to the outer surfaces of the rings *o* and toward each other. The 50 walls of the raceway structure are free to rotate upon their seats, this characteristic being of particular importance in connection with the inner raceway wall that rides upon the shaft. This structural characteristic is not to be limited to conical bearing structures. The conical or tapering surfaces at *g* and *p*, in the embodiment of the invention illustrated, slope toward each other, as do the conical or tapering surfaces 55 at *h* and *p*. Means are provided for effect-

ing relative adjustment between the two bearings at *g* and *h* so as to maintain the housing *e* coaxial with the shaft *a*, this adjustment, in the embodiment of the invention being described, being effected by turning the nut *q* on a threaded portion of the shaft *a* so as to force the split sleeve or collar *h* longitudinally of the shaft for the purpose stated. The dust guard *f'* not only desirably engages the shaft *a*, but also engages 75 the contiguous marginal portion *g'* of the roller container *g* so as to obstruct what would otherwise be a passage between the shaft and the contiguous pocket at *g'* for dust, water, or other foreign matter whose 80 way is forced along the shaft *a* past the dust guard.

As I have thus far specifically described one of many embodiments of my invention, I have disclosed the outer end of a non-rotating shaft upon which is supported a rotating body, such as a vehicle wheel, through the intermediation of my improved bearing, but it is to be understood that I do not limit the location of my improved 90 bearing to the outer end of the shaft, nor do I limit the use of my invention to the support of a rotating body upon a non-rotating shaft.

I have not deemed it necessary to show 95 obvious alternative arrangements, as various adaptations of the bearing of my invention may readily be made to suit different conditions.

As I have thus far specifically described 100 my invention, I have set forth a construction possessing many advantages. Each raceway wall is substantially of uniform thickness with the exception of the overturned edge portions of the raceway walls *i* *k* that are 105 slightly modified in thickness owing to the overturning or curling of the steel of which they are made. By making the raceway walls of uniform thickness, they take heat treatment uniformly in hardening. When 110 the raceway walls are being hardened, they are immersed with the larger ends first. Another important advantage gained by the construction of my invention is the automatic centering of each raceway wall upon 115 its seat, the raceway walls *i* and *k* automatically centering themselves upon the seats at *g* and *h* respectively, while the raceway walls *o* automatically center themselves upon their seats *p*, no careful manipulation 120 being required in assembling the parts, and no close dimensions having to be provided for in the seats for the raceway walls, thereby greatly simplifying the construction and reducing cost. In addition to the advantages 125 which have been above outlined, there is also the important advantage that, in the event of the clogging or locking of the rollers, a bearing is afforded between the rotating and non-rotating elements through the interme- 130

diation of the raceway walls, making a temporary plain bearing that will prevent the rotating and non-rotating parts *e* and *a* from being locked together when the rollers of the bearing are locked, the arrangement being preferably such that in the normal operation of the bearing, the raceway walls are adapted both to creep slightly so as to distribute the wear evenly thereupon, either raceway wall turning on its seat in the event of the locking of the complementary parts, the rollers or balls traveling in their paths with respect to the plain bearing for the raceway wall, said raceway wall being interposed between the rollers and the seat upon which said raceway wall may move. The raceway walls are normally free to move with respect to their seats whereby they may turn with respect to their seats without reorganization of the structure in the event of the rollers becoming locked.

In assembling the rollers within their containers *i* and *k*, the tapered rollers *l* and *m* and their separating balls are inserted in their relative order, two balls being last inserted in the annular pockets, thereby making a complete self-contained unit of the bearing. A niche *r* is provided in the edge of each overturned part *i* *k* to permit of the reception of the balls in the annular pockets. The balls and rollers not only rotate individually about their axes, but are also adapted to travel bodily while rotating. The pocket portions of the raceway walls *g* and *k* afford sufficient space to enable the balls properly to rotate and travel therein, and the edge portions of the overturned parts of the container *i* and also the container *k* project sufficiently toward the axis to form hooks over the balls, these hooks being cut away at *r*, as indicated in Figs. 2 and 3, to permit the balls to be received behind the hooks. The ball containing pockets are provided with flattened surfaces *s* at right angles to the axes of the tapered rollers for engaging the balls on end thrust of the tapered rollers, and also with flattened surfaces at *s'* parallel with the opposite face of the raceway wall *i* or *k*, clearance existing at *s* between the balls and the pocket wall and between the surfaces *s* *s'* to afford receiving space for foreign particles that might creep in.

In Fig. 4, I have shown a thrust or step bearing having parts possessing features of construction and functions similar to the parts of the bearing shown in Figs. 1, 2 and 3, and similar parts are given similar characters of reference. I do not deem it necessary to describe this bearing in detail.

While I have herein shown and particularly described the preferred embodiment of my invention, I do not wish to be limited to the precise details of construction shown, as changes may readily be made without de-

parting from the spirit of the invention, but,

Having thus described my invention, I claim as new and desire to secure by Letters Patent the following:—

1. In a bearing, the combination of a raceway structure comprising inner and outer members with rollers therebetween, and an element presenting a conical seat for one of said members of the raceway structure and with respect to which said member is freely rotatable to prevent locking of the bearing. 70

2. In a bearing, the combination of a raceway structure comprising inner and outer members with rollers therebetween, and inner and outer elements having plain conical seats for said raceway members and with reference to which the respective members are freely rotatable. 80

3. In a bearing, the combination of a raceway structure comprising inner and outer members with tapering rollers therebetween, and inner and outer elements having tapering seats for the respective members of the raceway structure and with respect to which said members are freely rotatable to prevent locking of the bearing. 85

4. In a bearing, the combination of a raceway structure comprising inner and outer members with tapering rollers therebetween, and inner and outer elements having tapering seats for the adjacent faces of the raceway structure members and with respect to which said members are freely rotatable respectively. 95

5. In a bearing, the combination of a raceway structure comprising inner and outer members with rollers therebetween, elements having tapering conical seats for said members respectively and with reference to which said members are free to turn, and means to adjust the raceway structure axially with respect to said elements. 100

6. In a bearing, the combination of raceway structures each embodying rollers, an element having conical seats for the respective raceway structures and with reference to which said structures are free to turn, and a single means to adjust said raceway structures axially with respect to their seats. 110

7. In a bearing, the combination of a raceway structure comprising inner and outer members with rollers therebetween, and a shaft having a tapering conical seat for the inner member of said raceway structure, said member being free to turn with respect to said seat to prevent locking of the bearing. 120

8. In a bearing, a raceway element comprising a metal sleeve having a main body portion of substantially uniform thickness a smooth bearing surface and integral curved edges so disposed as to partially overlie the main body portion to receive and retain anti-friction members. 125

9. In a bearing, a raceway element adapt- 130

- ed to receive and retain anti-friction members, comprising a metal sleeve of conical shape having its main wall portion of substantially uniform thickness and provided at its edges with integral curled portions to confine coöperating anti-friction members.
10. In a bearing, a raceway element adapted to receive and retain anti-friction members, comprising a conical metal sleeve having a smooth main wall portion of substantially uniform thickness and integral peripheral edge flanges having a cross sectional contour of substantially the arc of a circle partially overlying the main wall portion to confine coöperating anti-friction members.
11. In a bearing, a raceway element for anti-friction members comprising a tapering metal sleeve, the main wall portion of which is of substantially uniform thickness, the edge portions of said wall being of reduced thickness and curved on substantially the arc of a circle to form flanges to retain coöperating anti-friction members.
12. In a bearing, an inner raceway element comprising a conical metal sleeve having integral curled edges to receive and retain anti-friction members, and an outer raceway member comprising a freely movable ring of uniform thickness, and anti-friction members retained by the inner raceway and coöperating with both of said raceways.
13. In a bearing, the combination of an inner raceway comprising a tapering metal sleeve of substantially uniform thickness having its edge portions curled to partially overlie the body of the raceway, anti-friction rollers carried by said inner raceway and confined at their ends by said curled flanges, and a tapering ring, the inner surface of which seats on said rollers.
14. In a bearing, the combination of an inner raceway comprising a tapering metal sleeve of substantially uniform thickness having its edge portions curled to partially overlie the body of the raceway, anti-friction rollers carried by said inner raceway and confined at their ends by said curled flanges, and a tapering ring, the inner surface of which seats on said rollers, said ring being of uniform thickness throughout.
15. In a bearing, an inner raceway comprising a tapering metal container provided with integral curled edges and a smooth bearing surface of substantially uniform thickness between said edges, anti-friction balls confined within said curled edges, anti-friction rollers engaging the outer surface of said retainer and having their ends disposed between the balls confined by said edges, and a tapering ring seating on said rollers.
16. In a bearing, a raceway element adapted to receive and retain anti-friction members comprising a tapering metal sleeve of substantially uniform thickness having integral curled edges to retain the anti-friction members.
17. A bearing including inner and outer raceway members whose inner and outer surfaces taper in the same general direction, rollers interposed between said members, and tapering seats for the raceway members, one engaging the outer surface of the outer raceway member and the other engaging the inner surface of the inner raceway member, the inner member having integral curled edges to retain the rollers.

In witness whereof, I hereunto subscribe my name this 7th day of February A. D., 1910.

ISAAC A. GEORGE.
